MOTOR MOUNTING

Application filed November 30, 1929. Serial No. 410,766.

This invention relates to motor mountings.

It is among the objects of the present invention to provide a novel and improved mounting for outboard motors for motor boats.

A further important object of the present invention is to provide an outboard motor mounting whereby conventional type inboard motors may be used as outboard motors for motor boats.

A further object of the present invention is to provide an improved tiltable mounting for outboard motors.

Other objects of the present invention include the combination and interrelation of parts whereby a novel and improved motor mounting is provided which includes suitable supports and adjustable features, all of which will be simple, efficient and well adapted to meet the demands of economic manufacture.

Numerous other objects of the present invention will be apparent from a consideration of the following specification, taken in connection with the accompanying drawings, in which—

Figure 1 is a side elevation of a boat partly broken away and disclosing the present invention;

Figure 2 is a detailed section of the invention with the motor shown in dotted lines and illustrating the motor supports;

Figure 3 is a top plan view of the invention shown in Figures 1 and 2;

Figure 4 is a sectional view taken on the lines 4—4 of Figure 3;

Figure 5 is a detailed view showing a modified form of the invention taken on the lines 5—5 of Figure 6;

Figure 6 is an end elevation of a modified form of the invention.

Referring more particularly to the drawings, the numeral 10 indicates a boat, a sea sled being the type of boat chosen to illustrate the present form of the invention.

The boat is cut away in the rear to form a transom 11, as indicated in the top plan view of Figure 3. The sides 12 of the transom 11 are provided with centrally positioned motor supporting plates 13, each of which has a vertical slot 14 from which extend downwardly extending recessed slots 15. The plates 13 are adapted to be secured to the sides of the transom by suitable bolts, screws or the like, as indicated at 16 in Figure 2.

The motor generally indicated at 17 is herein illustrated as the conventional parallel vertical cylinder motor. It will be understood that the invention is not confined to the specific type of motor used, an important object of the invention being to provide means, however, for using the conventional inboard type of motor as an outboard motor on motor boats.

The motor 17 is provided with oppositely extending lugs 18 the ends of which terminate in heads 19, the arrangement being such that the lugs are movable in the slot 14 to be selectively received in the recessed slots 15, the heads 19 preventing accidental movement of the lugs from the plates.

It will be understood that the plates 13 are recessed behind the slots to provide for the reception of the head 20. Thus it will be seen that the lugs may be received within the slots by vertical downward movement so as to have the lugs enter the selected slot 15. It will also be seen that by the present arrangement the motor may be pivotally moved using the lugs as a fulcrum so that, as shown in dotted lines in Figure 1, the motor may be warmed up without the propeller being in the water.

For bracing the plates 13 and adjusting their distance from the front 21 of the transom, a substantially U-shaped brace 22 is provided secured by bolts as at 23 to the front 21 of the transom. The ends of the brace are channeled to receive therein parallel braces 24 extending forwardly from the

plates 13. The braces 24 are drilled as at 25 to receive therethrough a securing bolt 26 carried by the brace 22.

For securing the motor in proper tilted position as shown in Figure 1 whereby the propeller will be in the water to propel the boat, a pair of vertical brackets 27 are provided on the sides 12 of the transom and rearwardly from the plate 13. The brackets 27 are apertured as at 28 to receive therethrough a securing bolt 29 which passes through the upper ends 30 of upwardly and downwardly extending tie rods 31, the lower ends of which are secured by a bolt 32 to the extended casing 33 of the propeller shaft 34, as shown most clearly in Figure 4 of the drawings.

From the foregoing it will be readily seen that the present invention provides an adjustable mounting for outboard motors, the arrangement providing for the pivotal support of the motor and being adjustable longitudinally in the transom to accommodate various sizes of motor length.

By the use of the present invention it will be understood that the bolts 29 are disconnected, thus permitting tilting movement of the motor. The motor can then be tilted to the position shown in dotted lines in Figure 1 and warmed up without movement of the boat. When the motor is in the proper operating position it is tilted to the position shown in full lines in Figure 1, the bolts 29 are secured in the selected aperture 28, thus maintaining the motor in properly adjusted position.

Referring more particularly to Figures 5 and 6 of the drawings, it will be seen that the invention is adapted for application to boats which are not provided with the inward cut and transom. In this instance a substantially U-shaped bracket 36 is provided, the body of the U being bifurcated to be secured over the end boards 36 of the boat by a suitable securing nut 37. The upper ends of the U are notched as at 38 to receive the studs 18 of the motor 17. Thus the motor is adjustably mounted and is tiltable in its mounting and may be retained in tilted position by a conventional modification of the brackets 27 and the arms 31, or their equivalents. It will be seen in this form of the invention that the structure is adapted to adjustably support in pivotal position various types of conventional inboard motors for use as outboard motors.

It will also be readily understood that the invention is not confined to the specific structural details herein illustrated but that numerous changes and modification and the full use of equivalents may be resorted to without departing from the spirit and scope of the invention as outlined in the appended claims.

I claim:

1. In combination with a motor boat, means for pivotally mounting the motor, said means being adjustable longitudinally of the boat and including recessed plates adapted to receive extending lugs of the motor, said plates having vertical recesses and a plurality of receiving recesses communicating therewith. 70

2. In combination with a motor boat, means for pivotally mounting the motor, said means being adjustable longitudinally of the boat and including recessed plates adapted to receive extending lugs of the motor, said plates having a vertical recess and a plurality of receiving recesses communicating therewith, and supplementary means for securing the motor in tilted position. 80

3. In a motor boat the combination with a central rear cutout portion forming the motor transom, of means for pivotally mounting an inboard motor between the sides of said transom, said means including side plates each having a plurality of recesses carried by the sides of said transom to receive extending lugs from the motor. 85

4. In a motor boat the combination with a central rear cutout portion forming the motor transom, of means for pivotally mounting an inboard motor between the sides of said transom, said means including side plates each having a plurality of recesses carried by the sides of said transom to receive extending lugs from the motor, said plates having provision for securing them in place on the boat. 90

5. In a motor boat the combination with a central rear cutout portion forming the motor transom, of means for pivotally mounting an inboard motor between the sides of said transom, said means including side plates carried by the sides of said transom, said plates having a plurality of recesses adapted to receive extending lugs carried by said motor in said recesses, and means for adjustably bracing said plates with respect to the front of said transom. 105

6. In a motor boat the combination with a central rear cutout portion forming the motor transom, of means for pivotally mounting an inboard motor between the sides of said transom, said means including side plates carried by the sides of said transom, said plates having a plurality of recesses adapted to receive extending lugs carried by said motor in said recesses, and means for adjustably bracing said plates with respect to the front of said transom, and means rearwardly of said plates for supporting said motor in tilted position. 115

7. In combination with a motor boat, means for pivotally mounting the motor, said means being adjustable longitudinally of the boat while the motor is in the propelling position, and said means consisting of relatively ad- 120

justable parts each adapted for securement to the boat.

8. In combination with a motor boat, means for pivotally mounting the motor, said means being adjustable longitudinally of the boat while the motor is in the propelling position, and said means consisting of relatively adjustable parts each adapted for securement to the boat, two of said parts having provision 10 for receiving the extending lugs of the motor.
